Charles H. Frost

UNITED STATES PATENT OFFICE.

CHARLES H. FROST, OF CHICAGO, ILLINOIS.

CONSTRUCTION OF WALLS.

SPECIFICATION forming part of Letters Patent No. 364,241, dated June 7, 1887.

Application filed December 10, 1886. Serial No. 221,231. (No model.)

To all whom it may concern:

Be it known that I, CHARLES H. FROST, residing at Chicago, in the county of Cook and State of Illinois, and a citizen of the United States, have invented a new and useful Improvement in the Construction of Buildings, of which the following is a full description, reference being had to the accompanying drawings, in which—

10 Figure 1 is a vertical cross-section through a brick wall containing my invention. Fig. 2 is a plan of the same, the two inside and upper layers of brick being removed. Fig. 3 is an enlarged perspective showing my anchor 15 or binder.

15 My improvement is, primarily, designed to be used in connection with brick buildings which have a facing of pressed brick.

20 The object of the invention is to provide improved devices for binding the outer courses of the brick to the inside courses without laying any of the brick transversely, which I accomplish by providing the unexposed ends of the outer courses or layers of brick with vertical grooves, which can be readily formed in the brick in the process of manufacture, and by providing binders or anchors of peculiar construction, all as illustrated in the drawings, and hereinafter described.

25 That which I claim as new will be set forth in the claims.

30 In the drawings, A represents one of the brick to be used in the outer courses of the wall, each end of which brick is provided, as shown, with a vertical groove, a, which may be about one-half of an inch in depth.

35 B is an anchor or binder, which can be conveniently made of cast metal. The vertical end piece, b, of this binder is adapted to be 40 inserted into grooves in the ends of two adjoining bricks. The flat portion c of the binder is designed to be placed, in use, between the ends of two adjoining bricks, and the portion d of the binder is designed to rest 45 upon the bricks in the second or inner course. e is an upward projection from the inner end of the binder, which projection is designed to be embedded in the mortar between two layers

of brick. These binders may be used at suitable intervals and as often as in the judgment of the constructor may be necessary.

50 It is not necessary that all of the unexposed ends of the brick be provided with vertical grooves; but it will be more convenient to have them so manufactured.

55 When the binders are used in a wall as shown and described, the flanges of the vertical portion b of each binder will be in the grooves in the ends of the facing-brick, or in the mortar therein, and the projection d will 60 be embedded in the mortar of an adjoining course, and the facing-brick and the brick behind the same will be firmly bound and anchored together.

65 I have shown in the drawings a so-called "twelve-inch" brick wall. The outer courses or wall will usually be formed of pressed brick, the inside brick will be common brick, and the two inner walls may be bound together by laying the brick transversely from 70 time to time, as is common, which is not shown in the drawings.

75 My invention can be used with a so-called "eight-inch" wall, if desired, in which case the facing or outer wall will be bound to the inner wall, as before described, by means of my binders or anchors.

What I claim as new, and desire to secure by Letters Patent, is—

80 1. In a wall, the combination, with the outer and inner courses of bricks, of a binder, B, having a flat plate on the end which lies in vertical grooves in adjacent bricks of the outer course, a thin vertical portion which lies between the vertical faces of said bricks, and a 85 flat portion which lies between the horizontal faces of bricks in second or inner course, substantially as described.

85 2. The binder B, having a vertical part, b, at one end, a flat thin vertical part, c, a flat 90 horizontal part, d, and a projection, e, substantially as and for the purpose specified.

CHARLES H. FROST.
